UNITED STATES PATENT OFFICE

WILLIAM F. WELLS, OF CANNON FALLS, MINNESOTA

COMBINATION PENCIL SHARPENER AND ERASER

Application filed March 12, 1931. Serial No. 522,131.

This invention relates to writing and drafting equipment, particularly for the use of students and others who find it necessary to carry pencils, erasers, etc., about with them, and the primary object is to provide a combination pencil sharpener and eraser, in which the sharpener unit is embedded and anchored in the erasing unit, the latter of which may be formed of rubber, art gum, or other suitable material, with a result that the sharpener is not only less apt to become lost, as would otherwise be the case, but by being embedded in a substantially larger body unit, such as a large eraser, can be held and manipulated more efficiently and more easily than when it is made as a separate relatively small unit. Further and more specific objects will be disclosed in the course of the following specification, reference being had to the accompanying drawings in which:

Figure 1 is a perspective view of a combination pencil sharpener and eraser, embodying my invention,

Figure 2 is a fragmentary longitudinal sectional view on a plane indicated by the line 2—2 of Figure 1,

Figure 3 is a transverse sectional view on a plane indicated by the line 3—3 of Figure 1,

Figure 4 is a perspective view of the sharpener unit before being embedded in the eraser unit,

Figure 5 is a fragmentary rear elevation of a slightly modified form, and

Figure 6 is a fragmentary transverse sectional view on a plane indicated by the line 6—6 of Figure 5.

Referring to the drawings more particularly and by reference characters, A designates a block of eraser material, in which, when formed, the sharpener unit B comprises a conical member 4, to receive the end of the pencil to be sharpened, and this member 4 is slotted as at 5 and provided adjacent the slot with a cutting blade 6, so that as the pencil is turned with respect to the unit the shavings cut by the blade will escape through the slot. This method of sharpening is of course old in the art. In the present instance, however, it is necessary to expose certain parts of the sharpener, so that the

pencil can be inserted and to permit the escape of shavings, and adjustments to the blade 6; and this must be done without substantially weakening the eraser block so that it would be inclined to break in two. With these problems in mind I embed the sharpener unit with parts exposed as shown in the drawings, and provide the unit with integral oppositely extending anchor plates 7 and 8 that project into the opposite ends of the eraser block A. These plates are also preferably provided with angular ears or flanges 9, that are so arranged that they will not only firmly secure the anchor plates but will also tend to prevent the eraser parts adjacent the sharpener from breaking away in pieces. In order to more fixedly secure the sharpener unit B in the eraser block A the anchor plates 7 and 8 and flanges 9 are provided with openings 10 to receive the melted rubber when molding the block with the sharpener unit B embedded therein.

In Figures 5 and 6 is shown a modified construction in which the rear end of the sharpener unit designated B' is provided with a depending lip 11 that serves to additionally brace the unit B' in the eraser block A.

It is understood that suitable modifications may be made in the structure as disclosed, provided such modifications come within the spirit and scope of the appended claims.

Having now therefore fully illustrated and described my invention, what I claim to be new and desire to protect by Letters Patent is:

1. A combination pencil sharpener and eraser comprising a block of eraser material and a pencil sharpening unit embedded in said block, and means extending from the unit and embedded in the block for anchoring the unit therein.

2. A combination pencil sharpener and eraser comprising a block of eraser material and a pencil sharpening unit embedded in said block, and means extending from the unit for anchoring the same in the block, said means comprising plate members rigid with and extending from the unit into the block.

3. A combination pencil sharpener and eraser comprising a block of eraser material

and a pencil sharpening unit embedded in said block, said unit being provided with anchor plates extending to opposite sides thereof and embedded in said block for anchoring the unit therein.

4. A combination pencil sharpener and eraser comprising a block of eraser material and a pencil sharpening unit embedded in said block, said unit being provided with 10 rigid plate extensions, and angular flanges on said plate extensions for anchoring engagement in the block.

5. A combination pencil sharpener and eraser as in claim 4, the rigid plate extensions 15 and angular flanges being provided with openings to receive the eraser material.

6. A combination pencil sharpener and eraser, comprising a block of eraser material and a pencil sharpening unit embedded in 20 said block, said unit being provided with bracing members extending laterally of the unit, and a depending lip on one end of the unit and engaged by the material of the eraser.

25 In testimony whereof I affix my signature.
WILLIAM F. WELLS.
